(57) **CLAIM**

The ornamental design for roller applicator, as shown and described.

DESCRIPTION

FIG. 1 is a perspective exploded front top view of the roller applicator;

FIG. 2 is a perspective front top view of the assembled roller applicator;

FIG. 3 is a perspective rear view thereof;

FIG. 4 a top view thereof;

FIG. 5 is a bottom view thereof;

FIG. 6 is a side view thereof;

FIG. 7 is another side view thereof;

FIG. 8 is a front view thereof; and

FIG. 9 is a rear view thereof.

FIG. 10 is a perspective front top view of the roller applicator without rollers;

FIG. 11 a top view thereof;

FIG. 12 is a bottom view thereof;

FIG. 13 is a side view thereof;

FIG. 14 is another side view thereof;

FIG. 15 is a front view thereof; and,

FIG. 16 is a rear view thereof.

The broken lines in each figure illustrate portions of the roller applicator that form no part of the claimed design.
